UNITED STATES PATENT OFFICE.

THOMAS W. MITCHELL, OF OMAHA, NEBRASKA.

METALLIC PACKING.

SPECIFICATION forming part of Letters Patent No. 631,088, dated August 15, 1899.

Application filed December 1, 1898. Serial No. 697,985. (No model.)

To all whom it may concern:

Be it known that I, THOMAS W. MITCHELL, a citizen of the United States, residing at Omaha, in the county of Douglas and State 5 of Nebraska, have invented certain new and useful Improvements in Metallic Packings; and I do hereby declare the following to be a full, clear, and exact description of the same, reference being had to the accompanying 10 drawings, forming a part of this specification, and to the letters of reference marked thereon.

My present invention relates to packings such as are usually employed to make the 15 joints between moving parts—such, for instance, as the piston-rod and piston-head of an engine—steam, fluid, or gas tight; and the object of the invention is to provide a simple, easily-applied, and effective packing 20 which will adapt itself readily to the irregularities in the piston-rod or moving part, such as are usually occasioned by wear, particularly in horizontal engines, although it will be understood that the packing is applicable 25 to any desired form of rod or casing, and I do not wish to be limited to the particular application illustrated in connection with a piston-head or gland of a steam-engine.

Referring to the accompanying drawings, 30 Figure 1 is a plan or elevation of a gland of an engine with the top removed and the rod shown in section. Fig. 2 is a section at right angles to Fig. 1, on a reduced scale. Fig. 3 is a perspective view illustrating two of the 35 packing-rings and a section of the piston-rod passing therethrough, the rings being separated to illustrate their construction. Fig. 4 is a detail elevation of one of the packing-rings, showing the sections separated; and 40 Fig. 5 is a detail perspective view of one of the ring-sections. Figs. 6 and 7 are detail perspective views showing modified forms of the sectional rings.

Like letters of reference in the several figures indicate the same parts.

In the said drawings the letter A indicates a piston or similar rod adapted to slide longitudinally through a cylinder-head or abutment B, which cylinder-head or abutment 50 carries a packing-gland B', having a cover B²,

all of any ordinary or preferred construction and forming no part of my present invention.

The packings for preventing the escape of steam, fluid, or gas around the piston-rod in its travels back and forth through the gland are arranged within the gland and confined thereby, and in the preferred construction two separate rings are employed, which are duplicates of each other; but it will be understood that one ring or more than two rings 55 may be employed without in any wise departing from the invention. Each ring in its preferred form is made, preferably, of Babbitt metal and in two sections or segments, each adapted to encircle one-half, more or less, of 60 the piston-rod and both being confined within a retainer, as will be presently described.

The pressure within the gland is utilized to advance the sections of the packing-rings against the piston-rod, and, if desired, in addition flat springs may be employed for a like purpose, as is common in this art, and in order to prevent the ends of the sections from springing open when under pressure or when worn the ends of the sections are confined 75 between straight bearing-surfaces on the inner sides of the retainers, which bearing-surfaces, however, are parallel and arranged on opposite sides of the piston-rod, thereby permitting said sections to advance or retreat to 80 accommodate themselves to the irregularities in the rod or to take up wear as the same occurs. With such construction in order to prevent the passage of steam through the ring between the sections the sections are 85 made with coöoperating projections or bearing-surfaces lying in planes parallel with the direction of bodily movement of the sections. Thus in the advance and retreat of the sections toward and from each other no joints 90 are opened and no steam or pressure can escape between the sections.

Referring particularly to Figs. 1 to 5, it will be seen that the sections of the packing-ring are lettered C, each being substantially semi-circular and adapted to embrace the piston-rod A. Each of the sections is a duplicate of the others, and they are preferably made interchangeable, each being provided at one end with a wall c on one side and a recess or 100

seat c' on the opposite side and with an outer flat face c^2 , which is adapted to rest against a corresponding face or bearing-surface d^2 in the retainer D . The opposite end of each 5 of the sections in this preferred form has a projection c^3 , adapted to fit within the recess or seat c' in the coöperating section, and a seat c^4 , adapted for the reception of the wall c on the opposite section. As thus constructed, 10 the two sections when brought together will fit tightly, and it will be particularly noted that all of the contacting surfaces will rub together when the sections are advanced toward or moved away from each other and are 15 arranged in planes extending parallel with the surface c^2 or parallel with the flat face of the rings themselves. Thus they are constantly in contact during the movements of the sections toward and from each other, and the 20 joints are so broken by the walls c that no steam or pressure can pass through between the sections and so escape around the piston-rod.

Where two or more rings are employed in 25 the same gland, they are preferably arranged to break joint, as illustrated clearly in Fig. 3, and this relative position is maintained by means of keys and slots $D' D^2$ in the retainers D .

Obviously the idea of providing packing-ring segments or sections with parallel substantially straight bearing-surfaces on the exterior, with a retainer having corresponding bearing-surfaces for preventing expansion or 35 distortion of the sections or segments, and in providing the meeting ends of said segments or sections with plain flat bearing-surfaces which move upon each other in lines parallel with the retaining-surfaces may be embodied in a number of forms, and in Fig. 6 I have 40 shown a construction which corresponds to the construction shown in Figs. 1 to 5, save that the projection c^3 and recess c' are omitted. In this form, then, the sections C^4 at one 45 end are provided with a flat surface c^5 , corresponding to the flat surface c^2 , and on the inner side they are provided with a flat surface c^6 , while at the opposite end a flat surface c^7 is provided, all of said flat surfaces being 50 arranged in parallel planes. The two sections as thus constructed when brought together will be reversed with relation to each other and will occupy the position illustrated in Fig. 6—that is to say, the flat surfaces c^6 and 55 c^7 will contact with each other and form sliding bearings and the flat surfaces c^5 will rest against and take their bearing on the parallel surfaces d^2 in the retainers D . If desired, also, the sections may each have a wall extending 60 up for contact with the flat faces of the retainer, and such a construction I have illustrated in Fig. 7, wherein it will be seen that each of the sections is provided with a vertical wall E at one side and at the opposite end with a wall E' , which overlaps the wall E when the two sections are brought together. The outer faces or edges of each of

the walls E and E' are made flat at E' and adapted to take a bearing on the surface d^2 of the retainers, and in addition the said sections are provided with surfaces $e e'$, arranged parallel with the surfaces E^2 , thereby forming a construction through which it is practically impossible for any pressure to pass when the sections are properly pressed together and held against the rod. 75

Any usual means may be employed to retain the packing-rings and their retainers, which are preferably, though not necessarily, independent of the gland up against the end 80 of the gland, and I have illustrated a spring F for accomplishing this purpose, which spring F bears against a plate or washer F' , and the latter in turn seats against the innermost packing-ring. 85

Having thus described my invention, what I claim as new, and desire to secure by Letters Patent of the United States of America, is—

1. In a metallic packing the combination 90 with a retainer having oppositely-arranged parallel internal bearing-surfaces, of packing-ring sections movable bodily toward and from each other in a direction parallel with the bearing-surfaces in the retainer and having 95 external surfaces working in contact with said internal bearing-surfaces in the retainer, the meeting ends of said packing-ring sections having coöperating overlapping projections provided with contacting bearing-surfaces lying in planes parallel with the direction of bodily movement of the sections and at right angles to the plane of the internal 100 surfaces in the retainer and other contacting bearing-surfaces lying in planes parallel with 105 said internal bearing-surfaces in the retainer; substantially as described.

2. In a metallic packing the combination 110 with a retainer having internal oppositely-arranged parallel bearing-surfaces, of packing-ring sections having external bearing-surfaces coöperating with said internal bearing-surfaces in the retainer, the meeting ends of 115 said sections being provided with projections c^3 and recesses c' having contacting faces lying in planes parallel with the direction of bodily movement of the sections; substantially as described.

3. In a metallic packing the combination 120 with the retainer having the internal oppositely-arranged parallel bearing-surfaces, of the packing-ring sections mounted within 125 said retainer and having oppositely-arranged parallel external bearing-surfaces coöperating with the bearing-surfaces in the retainer, the meeting ends of the said sections being formed with walls c and recesses c' , the overlapping faces between said meeting ends lying in planes parallel with the direction of bodily movement of the sections; substantially as described.

4. In a metallic packing the combination 130 with two retaining-rings, each having oppositely-arranged parallel internal bearing-sur-

faces, with means for retaining said rings with the bearing-surfaces out of alinement with each other, of segmental packing-rings mounted within the retaining-rings and having external bearing-surfaces coöperating with the internal bearing-surfaces in said rings, the meeting ends of said segments being overlapped and provided with bearing-

surfaces lying in planes parallel with the internal bearing-surfaces in the retaining-¹⁰ rings; substantially as described.
